No 69

Des. 69

Adam Hampton, New York City.

Letters Patent (Design No 69) dated 25th July 1846.

The Schedule referred to in these Letters Patent and
making part of the same.

To all whom it may concern:

Be it known that I, Adam Hampton of the City County and State of New York have produced a new design to be cast in iron, which when thus cast is termed a fire place-grate frame, and I do hereby declare that the following is a full, clear and exact description of the same reference being had to the annexed drawing making part of this specification.

The nature of my production consists in the arrangement

of moulding and figures forming a parlor grate in manner as herein specified.

Make a moulding of an irregular Ω form, a, this may be considered as partaking of the Ionic order of Architecture, and is carried allround the inside, and form the inside of grate,

in a deep projection of convex and concave curves terminating upon an angular base. This is surrounded by b, a continuous course of scroll and leafage work of the Louis X. V style of architecture, beginning at the centre of the top of the frame, with a small centre piece, on each side of this is a scroll and beyond that a leaf running to the end, or angle of the corners, bearing a scroll and leaf alternately - From the corner or mitre the same is continued to the base beginning with a leaf and followed by a scroll, in the same manner on both sides. I purpose when desirable to substitute a plain moulding for this part.

This terminates upon a level base c, which surrounds it. We may have a convex or concave receding moulding d, which terminates upon the ornamental bead moulding e, of the outside which is further surrounded by a plain rounded moulding f, which is the extreme outside the whole being so arranged as to dispose of the above mouldings and ornaments in the form and manner (as shown in the drawings) of a projecting centre or receding extreme, grate, composed of said ornaments -

What I claim as my production and wish to secure by Letters Patent is the herein specified design for a grate composed of mouldings and ornaments as set forth.
